[57] CLAIM

The ornamental design for a container body for liquids having internally ribbed reinforcements, as shown and described.

DESCRIPTION

FIG. 1 is a front elevational view of a container body for liquids having internally ribbed reinforcements showing our design with the rear elevational view of the container body being a mirror image of FIG. 1; FIG. 2 is a side elevational view thereof taken from the right of FIG. 1, a left side elevational view of the container body being a mirror image of FIG. 2; FIG. 3 is a top plan view thereof; FIG. 4 is a bottom plan view thereof; and, FIG. 5 is a fragmentary horizontal sectional view taken along the line 5—5 of FIG. 1. The broken line showing of a neck finish in FIGS. 1 and 2 is for illustrative purposes only and does not form part of the claimed design.
